UNITED STATES PATENT OFFICE.

SEYMOUR FOX, OF CLEVELAND HEIGHTS, OHIO, ASSIGNOR TO RADIO PRODUCTS MANUFACTURING COMPANY, OF CLEVELAND, OHIO, A CORPORATION OF OHIO.

DESIGN FOR RADIO RECEIVING-SET CASE.

Application filed June 7, 1924. Serial No. 9,821. Term of patent 7 years.

To all whom it may concern:

Be it known that I, SEYMOUR Fox, a citizen of the United States, residing at Cleveland Heights, in the county of Cuyahoga and State of Ohio, have invented a new, original, and ornamental Design for Radio Receiving-Set Case, of which the following is a specification, reference being had to the accompanying drawing, forming a part thereof.

In the drawing, the figure is a perspective of the case.

I claim:

The ornamental design for radio receiving set case, substantially as shown in the drawing hereof.

SEYMOUR FOX.
